SHELF UNIT

Walter G. Anders, Kenmore, N.Y., assignor to Sperry Rand Corporation, New York, N.Y., a corporation of Delaware

Filed Aug. 15, 1963, Ser. No. 302,365
5 Claims. (Cl. 211—184)

The present invention relates to new and useful improvements in shelf units and more particularly to divider panels that are used therein to divide a shelf unit into a selected number of compartments.

Shelf units which employ vertically disposed divider panels at spaced intervals along a horizontal shelf portion of the unit to provide a plurality of compartments along the shelf are well known. Various articles or material as for example, file folders, and books or the like, are stored in the compartments. The number of dividers and compartments formed thereby is optional according to the needs of the user and the width of the compartments may be varied by providing means for shifting the dividers to different positions on the shelf.

Certain shelf units of this type in addition to having a horizontal shelf portion, also includes a horizontal top panel and spaced vertical end walls. Shelf units of the latter type are open at the front and rear thereof whereby material stored in the compartments is readily accessible to a user from either the front or rear of the shelf. Various means such as screws, pins or lugs have been used in the past to attach a divider to the shelf and top panel of a shelf unit of the latter type. In addition, various locking devices extrinsic to the divider have been used to lock the divider to the shelf of the unit to prevent accidental dislodgement of the divider. The latter devices and arrangements result in complicated forming of dividers and which dividers are not readily repositionable on the shelf.

An object of the present invention is to provide a shelf unit of novel construction.

Another object is to provide a novel shelf unit having a divider which may be readily repositioned along the shelf of the unit.

A further object is to provide a divider of novel construction and which divider is formed with integral means for locking the divider to a shelf unit.

A still further object is to provide a novel and economical divider which is easily mounted on and locked to a shelf and which divider may be readily unlocked and repositioned along the shelf.

The present invention contemplates in one embodiment thereof, a shelf unit which includes a horizontally disposed shelf or base panel and a horizontally disposed top panel which is vertically spaced from the base panel. The base and top panels are each provided with rows of aligned mounting slots. Vertically disposed sheet-like dividers having tabs formed on opposite edges are mounted at spaced intervals on the unit with the tabs inserted in at least a pair of aligned slots in the shelf and top panel. A resilient locking finger is formed on each divider and which finger is bent away from the surface of the divider to lie adjacent the bottom surface of the top panel to lock the divider to the shelf unit. A divider is readily removed from the shelf through depression of the locking finger into alignment with adjacent tab projections on the top edge of the divider and then raising and pivoting the divider out of the mounting slots.

The above and other objects and advantages of the invention will appear more fully hereinafter from a consideration of the detailed description taken together with the accompanying drawings wherein one embodiment of the invention is illustrated.

2

In the drawings:

FIG. 1 is a perspective fragmentary view of a shelf unit embodying the present invention.

FIG. 2 is a front elevational view of the shelf unit of FIG. 1 with part of the unit broken away to show portions of a divider in locked position on the shelf unit;

FIG. 3 is a sectional view taken on the lines 3—3 of FIG. 2;

FIG. 4 is a fragmentary front elevational view of portions of the shelf unit showing a divider in a raised position and disengaged from the base panel during positioning thereof on the shelf unit; and

FIG. 5 is a view similar to FIG. 4 wherein the divider is pivoted from the position of FIG. 4 to an inclined position relative to the top panel during removal of the divider from the shelf unit.

Referring now to the drawings for a more detailed description of the present invention and more particularly of FIGS. 1 and 2 wherein one preferred embodiment is clearly illustrated, a shelf unit is generally designated by the numeral 10. Shelf unit 10 is formed from sheet metal material and includes a horizontal base panel or shelf portion 11 on which may be stored various articles (not shown) which may include among others, articles such material as, file folders, books or the like. Shelf 11 is supported by and between a pair of spaced vertical end walls 12 and 13, respectively (FIG. 2). End walls 12 and 13 are each provided with flange portions 14 (partially shown in FIG. 2) and which flange portions 14 are suitably secured to the opposite ends of shelf 11 in any suitable manner as by spotwelding. A top wall or upper horizontal panel 15 (FIG. 1) having inturned marginal portions 16 and 17, respectively, along the front and rear edges thereof is provided for shelf unit 10. The spaced opposite ends of top panel 15 are secured to flange portions 18 (partially shown in FIG. 2) of each end wall 12 and 13 in any suitable manner such as by welding.

An inverted elongated U-shaped reinforcing member 19 is secured to the top surface (FIG. 1) of top panel 15 intermediate front and rear marginal portions 16 and 17 thereof. A pair of U-shaped longitudinally extending reinforcing members 20 and 21 are arranged beneath shelf 11 (FIG. 1) adjacent the front and rear edges of shelf 11. Member 20 is provided with a pair of flange portions 22 and 23 which extend at right angles from member 20 and which flange portion 22 and 23 are secured to the bottom surface of shelf 11 as by welding. An upright lip 24 is provided on flange portion 22 of member 20 and which lip 24 projects above and extends along the front edge of shelf 11 (FIG. 1). Member 21 is provided with a similar pair of flange portions 25 and 26 secured to the bottom of shelf 11 with a lip 27 provided on flange portion 26 which projects above and extends along the rear edge of shelf 11. Lips 24 and 27 serve to prevent articles from moving off the front and rear edges of shelf 11.

Shelf unit 10, as described, is well adapted for use with an automated file unit such as a conveyor driven file unit (not shown). It is to be understood, however, that the present invention, which is to be hereinafter fully described and as will be readily apparent to those skilled in the art is readily adaptable to other type shelf units such as stationary bookstacks or the like.

As seen in FIG. 1 a row of laterally spaced rectangular shaped mounting slots or apertures 28 is provided along the front of shelf 11 and which slots 28 are spaced from and extend in a direction normal to lip 24. A second row of laterally spaced apertures of mounting slots 29 is provided along the rear of shelf 11 and which slots 29 are spaced from and extend in a direction normal to lip 27. Each slot 29 of the rear row is arranged to be in alignment with a slot 28 of the front row. Top panel 15

(FIG. 1) is provided with a single row of laterally spaced elongated mounting slots or apertures 30 of rectangular configuration intermediate marginal portions 16 and 17. Each slot 30 is in vertical alignment with a pair of aligned slots 28 and 29 in shelf 11, whereby an imaginary plane drawn to intersect top panel 15 and panel 11 at right angles contains a slot 30 and an associated pair of slots 28 and 29.

As seen in FIG. 2, a plurality of vertically arranged sheet-like divider panels 31 of sheet metal material are mounted on shelf unit 10 at spaced intervals along shelf 11. Dividers 31 form a plurality of compartments 32 on shelf 11 and in which compartments 32 various articles (not shown) may be stored on shelf 11. A pair of spaced downwardly extending tab projections 33 (FIGS. 1 and 3) are provided at the bottom edge of each divider 31 and are accommodated in a pair of aligned slots 28 and 29 in shelf 11. A second pair of tab projections 34 are formed at the top edge 31A (FIG. 3) of each divider 31 and which tabs 34 are accommodated within and project through its associated elongated mounting slots 30 in top panel 15 and which slot 30 is in vertical alignment with the slots 28 and 29 in which tabs 33 of the divider 31 are disposed. Top edge 31A (FIG. 3) of divider 31 adjacent tabs 34 is formed so as to be spaced a given distance from the bottom of panel 15 for purposes to be hereinafter explained. A resilient locking finger 35 is formed in the top of each divider 31 intermediate the pair of tab projections 34 thereon and which finger 35 is normally bent away from tabs 34 and the surface of divider 31 whereby the top edge of finger 35 (FIG. 2) lies closely adjacent the bottom of top panel 15 intermediate a pair of adjacent slots 30 (FIG. 2). Dividers 31 are thereby securely mounted on shelf unit 10 with the side walls of slots 28, 29 and 30 preventing lateral movement of tabs 33 and 34. Similarly, locking finger 35 in its bent position is arranged to engage the bottom of top panel 15 to restrain such upward vertical movement of divider 31 to prevent disengagement of tabs 33 from slots 28 and 29.

In the described arrangement, let it be assumed that a user desires to expand or reduce the lateral width of a selected compartment 32. This is accomplished by repositioning of a divider 31. Firstly, the user grasps divider 31 and applies finger pressure to locking finger 35 with his thumb in the direction of the arrow designated A in FIG. 4 to align locking finger 35 with tab projections 34. Divider 31 is then moved upwardly so that locking finger 35 enters slot 30, and movement of divider 31 continued until tabs 33 are disengaged from or raised out of mounting slots 28 and 29 (FIG. 4). It will be understood that the distance between edge 31A and the bottom surface of panel 15 as seen in FIG. 3 is greater than the distance between edge Y and the edge 33A of tab 33 to permit tabs 33 to be disengaged from slots 28 and 29 when the divider 31 is raised as described heretofore. Divider 31 is then swung to the right to the position shown in FIG. 5 by pivoting finger 35 and tabs 34 against the side walls of slot 30. In pivoted position (FIG. 5) divider 31 is then moved in the direction of the arrow designated B whereby tabs 34 and finger 35 are moved downwardly to disengage slot 30 to release divider 31 from shelf unit 10.

Let it be assumed that it is then desired to reinsert the divider 31 in a different set of aligned slots 28, 29 and 30 on shelf unit 10. In such event, divider 31 is mounted following a procedure reverse to the described manner in which divider 31 was removed from shelf unit 10. The user grasps divider 31 and depresses locking finger 35 with his thumb into alignment with tabs 34 and inserts locking finger 35 and tabs 34 at an angle (as seen in FIG. 5) into a selected slot 30 in top panel 15 until edge 31A engages the bottom of panel 15. Divider 31 is then pivoted to the left (looking at FIG. 5) to the position shown in FIG. 4, and in which position divider 31 lies in a plane normal to shelf 11 with tabs 33 thereof in align-

ment with a pair of aligned slots 28 and 29 in shelf 11. Divider is then released or moved downwardly allowing tabs 33 to drop into slots 28 and 29. In moving downwardly a sufficient distance resilient locking finger 35 becomes disengaged from the side walls of slot 30 as tabs 33 enter slots 28 and 29 and finger 35 springs to the left (FIG. 2) beneath the bottom of top panel 15. In such position finger 35 is prevented from accidentally reentering slot 30.

It will be apparent from the foregoing description that the novel shelf unit and divider arrangement described has many advantages in use. One advantage of divider 31 as described is that it is provided with an integral resilient locking member 35 which results in an economical one piece construction wherein the divider and locking member are stamped from the same piece sheet metal material. Another advantage is that divider 31 is readily mounted on or removed from a shelf unit with a minimum amount of effort.

Although one embodiment of the present invention has been illustrated and described in detail it is to be expressly understood that the invention is not limited thereto. Various changes can be made in the design and arrangement of parts without departing from the spirit and scope of the invention as the same will now be understood to those skilled in the art.

What is claimed is:

1. In a shelf unit of the class described,
  - (a) a first panel having a row of laterally spaced apertures,
  - (b) a second panel arranged in a plane spaced from and parallel to said first panel and having a row of laterally spaced apertures, each arranged to lie in an imaginary plane intersecting said first and said second panels and containing an aperture of said first panel,
  - (c) a sheet-like divider arranged between said first and second panels and having opposite edges disposed in a plane intersecting each of said panels at right angles,
  - (d) spaced tab projections provided on said spaced opposite edges of said divider and each tab projection disposed in an aperture of an associated pair of apertures of said first and second panels contained within one of said imaginary planes, and
  - (e) resilient locking means formed on said divider projecting outwardly of said one imaginary plane to lie adjacent the surface of one of said panels to prevent disengagement of said tab projections from said one pair of associated apertures.
2. In a shelf unit of the class described,
  - (a) a horizontal shelf panel having spaced first and second rows of laterally spaced and aligned apertures,
  - (b) a horizontal top panel arranged in a plane spaced vertically from and parallel to said shelf panel,
  - (c) said top panel having a row of laterally spaced elongated apertures each arranged to lie in an imaginary plane intersecting said shelf and top panels and containing a pair of apertures in said first and second rows of said shelf panel,
  - (d) a sheet-like divider arranged between said panels and having tab projections formed thereon disposed in apertures of said shelf and top panel contained within one of said imaginary planes, and
  - (e) resilient locking means on said divider projecting outwardly of said one imaginary plane to lie adjacent a surface of one of said panels to prevent disengagement of tab projections from said apertures.
3. The shelf unit of claim 2 wherein said divider is provided with a spaced pair of said tab projections on the top edge thereof and a spaced pair of said tab projections on the bottom edge thereof, said tabs on the bottom edge thereof each inserted in the pair of apertures of said first and second rows of said shelf panel lying within said one imaginary plane and each of said

spaced pair of said tab projections on said top edge inserted in the one aperture of said top panel lying within said one imaginary plane.

4. In a shelf unit of the class described,

- (a) a horizontal shelf panel having spaced first and 5 second rows of laterally spaced apertures,
- (b) a horizontal top panel arranged in a plane spaced vertically from and parallel to said shelf panel,
- (c) said top panel having a row of laterally spaced 10 apertures each arranged to lie in an imaginary plane intersecting said shelf and top panels at right angles and containing an aperture in said first row and an aperture in said second row of said shelf panel,
- (d) a vertically disposed divider member arranged in one of said imaginary planes and having a pair of tab 15 projections on one edge thereof inserted in said apertures of said shelf panel and having tab projections on the opposite edge thereof inserted in the aperture of said top panel contained in said one imaginary plane, and
- (e) resilient locking means formed on said divider projecting outwardly of said imaginary plane to lie adjacent the surface of said top panel to prevent disengagement of said tab projections from said apertures,

5. In a shelf unit of the class described,

- (a) a horizontal shelf panel having a first and a second row of laterally spaced mounting slots,
- (b) a horizontal top panel arranged in a plane spaced vertically from and parallel to said shelf panel,
- (c) said top panel having a row of laterally spaced 30

elongated mounting slots each arranged in an imaginary vertical plane intersecting said top panel and shelf panel at right angles and containing a mounting slot in said first row and a mounting slot in said second row of said shelf panel,

- (d) a detachable sheet-like divider disposed in one of said imaginary planes,
- (e) spaced tabs provided on the bottom edge of said divider and each inserted in a slot of said first and second row of slots of said shelf panel lying in said one imaginary plane,
- (f) spaced tabs provided on the top edge of said divider and inserted in the slot of said top panel lying in said one imaginary plane, and
- (g) a resilient finger member formed on said divider intermediate said spaced tabs on said top edge thereof projecting outwardly of said imaginary plane to lie adjacent the surface of said top panel to prevent disengagement of said tab projections from said mounting slots.
